Primary Examiner — John Windmuller*Assistant Examiner* — John R Yeh(74) *Attorney, Agent, or Firm* — Cantor Colburn LLP(57) **CLAIM**

We claim, the ornamental design for a dish washer, as shown and described.

DESCRIPTION

FIG. 1 is the front perspective view of a dish washer showing our new design;

FIG. 2 is the front elevation view thereof;

FIG. 3 is the rear elevation view thereof;

FIG. 4 is the left-side elevation view thereof;

FIG. 5 is the right-side elevation view thereof;

FIG. 6 is the top-side plan view thereof;

FIG. 7 is the bottom-side plan view thereof; and,

FIG. 8 is the front perspective view thereof, with a door of the dish washer being shown in another position.

The broken lines illustrating portions of the dish washer are for environmental purposes only and form no part of the claimed design.
